(57) **CLAIM**

The ornamental design for a j-bar chair component, as shown and described.

DESCRIPTION

FIG. 1 is a front view of the component;

FIG. 2 is a rear view of the component;

FIG. 3 is a side view of the component;

FIG. 4 is a top plan view of the component; and

FIG. 5 is a front view showing the component incorporated, in use, in a chair which is shown as background;

FIG. 6 is a rear view of FIG. 5;

FIG. 7 is a side view of FIG. 5; and,

FIG. 8 is a top plan view of FIG. 5.

The broken lines showing of a chair in FIGS. 5-8 are for illustrative purposes only and form no part of the claimed design.
